UNITED STATES PATENT OFFICE

2,618,143

CONTAINER FOR WASHING STOCKINGS

Donald McConaughy, Darien, Conn., assignor to
 Production Associates, Incorporated, Fairfield,
 Conn., a corporation of Connecticut

Application July 21, 1948, Serial No. 39,975

5 Claims. (Cl. 68—213)

1

The present invention relates to apparatus for washing clothing. More particularly, it has to do with a new and improved device for washing small articles of clothing such as stockings, for example, in a simple and highly effective manner.

In recent years, many women have adopted the practice of washing their stockings every evening before retiring. Although this custom has become widespread, no suitable device designed expressly for this and like purposes has been made available. As a result, washing operations of this type are almost universally carried out in a bathroom sink with consequences that are often a source of considerable annoyance to others.

It is an object of the invention, accordingly, to provide a novel device for washing small articles of clothing and the like such as stockings, for example, which is free from the undesirable features of the methods employed heretofore for this purpose.

Another object of the invention is to provide new and improved washing apparatus which has no moving mechanical parts yet produces a highly effective washing effect.

These and other objects of the invention may be attained by providing a washing device comprising separable portions adapted to be assembled together to form a closed container of suitable size to accommodate the articles to be washed. The container is provided with at least one transverse partition intermediate the ends thereof which is formed with vane-like passages. The vane-like passages are suitably designed to give a circular whirling motion to liquid in the container when the latter is shaken up and down.

In a preferred embodiment, the container comprises two parts each having a transverse partition containing vane-like passages. The vane-like passages in the transverse partitions are preferably oppositely directed so that a circular whirling motion is given to the contents of the container upon up and down shaking thereof.

Additional objects and advantages of the invention will be apparent from the following detailed description of a typical embodiment, taken in conjunction with the accompanying drawings, in which:

Fig. 1 is a view in elevation of a washing device constructed according to the invention, partially broken away to show the details of construction;

Fig. 2 is a view in perspective of one of the partitions in the device of Fig. 1;

Fig. 3 is an enlarged partial perspective view

2

in section, taken along line 3—3 of Fig. 2, looking in the direction of the arrows; and

Fig. 4 is a view in elevation of a modified form of washing device utilizing a drum-like container for the articles to be washed.

In the representative embodiment shown in Fig. 1, the novel washing device of the invention is shown as an elongated container 10, substantially oval in shape, and having a bottom member 11 and a top member 12. The bottom member 11 may be provided with a shouldered portion 13 at its upper end which is adapted to be snugly fitted within a corresponding annular recessed portion 14 in the top member 13, as shown. The bottom member 11 may be provided with a suitable base 15 on which it is supported when not in use.

Mounted within the bottom member 11 is a transverse disc-like partition 16 provided with a circular array of vane-like elements 17, as shown in greater detail in Fig. 2. The partition 16 may be provided with a shouldered portion 18 which is adapted to be snugly fitted into a corresponding shouldered portion 19 formed in the bottom member 11. The partition 16 may be secured in the bottom member 11 in any suitable manner as, for example, by means of cooperating threads 20 and one or more grooves 21 may be formed in the upper face of the partition 16, as shown in Fig. 2, to facilitate the removal thereof when desired. Also, the transverse partition 16 may be provided with a substantially conical member 22 which serves to deflect fluid in the container 10 to the vane 17 as will be described in greater detail hereinafter.

Within the upper member 12 is mounted another transverse partition 16' which is identical with the transverse partition 16 and corresponding parts of the former have been designated by corresponding primed reference characters. Preferably, the transverse partitions 16 and 16' are located a sufficient distance apart to form a chamber therebetween that will be large enough to accommodate the article or articles of clothing that are to be washed.

As shown in greater detail in Fig. 3, the vanes 17 in the transverse member 16 should be disposed at a suitable angle so that when the direction of motion of the container 10 is reversed from upwardly to downwardly while the container 10 is being shaken, liquid therein will move upwardly and will be deflected toward the right in the direction of the arrows in Fig. 3. The partition 16' produces a similar rotary motion of the contents of the container 10 when

the direction of motion of the container 10 is reversed from downwardly to upwardly during the shaking thereof. By virtue of this construction, the liquid entering the chamber between the partitions 16 and 16' is given a rotary whirling motion which produces vigorous agitation of the articles to be washed and results in a highly effective cleaning action.

In operation, the top member 12 is removed and a quantity of suitable cleaning solution, such as a soap solution, is poured into the bottom member 11. In a modification designed specifically for washing a pair of ladies stockings, for example, about a cup and a half of soapy water may be sufficient. The stockings, or other articles to be washed, are then placed on the top of the transverse partition 16 and the top member 12 is inserted over the bottom member 11. The container 10 is then grasped between the hands and shaken vigorously as if it were a cocktail shaker, for example. As pointed out above, each time the container 10 is moved upwardly, the soap solution enters the space between the transverse partitions 16 and 16' with a vigorous whirling motion, and each time the container 10 is moved downwardly, liquid passing through the transverse partition 16' is given a similar whirling motion. As a result, the stockings within the container are vigorously agitated in the soap solution and may be effectively cleaned in a relatively short period of time.

The top member 12 is then removed, the soapy water poured out and clean rinsing water added. The top member 12 is then replaced and the container 10 is again shaken for a sufficient period of time to rinse the stockings and remove the soiled soapy water therefrom.

From the foregoing description, it will be readily apparent that the invention provides a simple yet highly effective device for washing small articles of clothing, such as stockings, for example. It is handy to use and eliminates the undesirable consequences resulting heretofore from washing small articles of clothing, such as stockings, for example, in a bathroom sink.

It will be understood that the washing device of the invention may be made in any desired shape or form. Instead of the oval shape of the modification illustrated in the drawings, the washing device might be made cylindrical or in any other desired shape. Also, the vanned partitions 16a and 16a' might be secured to opposite ends of a cylindrical member 23 to form a drum-like container for the articles as shown in Fig. 4. The drum-like container so formed might be designed to fit within and to be retained in position by the cooperating container members 11 and 12. One end of the drum-like container (i.e., the transverse partition 16a') might be made removable to facilitate the insertion of articles to be washed.

While the novel washing device of the invention may be manufactured out of any suitable materials, it lends itself particularly to the use of plastics. In such case, colored plastics may be employed and the device may be made in pastel shades to match bathroom fixtures, or in any other shades that may be particularly appealing to women. Obviously, the device may be made of other suitable materials, such as aluminum, for example.

The specific embodiment described above, by way of illustration, is not intended to be in any way restrictive since it will be readily apparent

that modifications and changes can be made within the scope of the following claims.

I claim:

1. A washing device for small garments and the like comprising in combination, a plurality of mating portions which when mated form an elongated liquid tight chamber within said device, each of the portions forming an end of said device having a smoothly curved interior wall surface, and a hollow, garment receiving container removably mounted in fixed position in said chamber intermediate the ends thereof, said container having perforated opposite ends forming longitudinally spaced apart perforated transverse partitions in said device, whereby upon shaking said device liquid within said device is adapted to pass from one end thereof to the other through said garment receiving container.
2. A washing device for small garments and the like comprising in combination, a plurality of mating portions which when mated form an elongated liquid tight chamber within said device, each of the portions forming an end of said device having a smoothly curved interior wall surface, and a pair of longitudinally spaced apart, transverse partitions forming a garment receiving compartment intermediate the ends of said device, each of said partitions being provided with a radial array of closed conduits extending therethrough longitudinally of the device, each of said conduits being relatively elongated in the radial direction and being relatively narrow in a direction substantially perpendicular to said radial direction.
3. A washing device for small garments and the like comprising in combination, a plurality of mating portions which when mated form an elongated liquid tight chamber within said device, each of the portions forming an end of said device having a smoothly curved interior wall surface, and a pair of longitudinally spaced apart, transverse partitions secured to the interior walls of said end portions, respectively, and forming a garment receiving compartment intermediate the ends of said device, each of said partitions having a substantially radial array of longitudinally extending closed conduits formed therein, each of said conduits being relatively elongated in the radial direction and being relatively narrow in a direction substantially perpendicular to said radial direction.
4. A washing device for small garments and the like comprising in combination, a plurality of mating portions which when mated form an elongated liquid tight chamber within said device, each of the portions forming an end of said device having a smoothly curved interior wall surface, a pair of longitudinally spaced apart, transverse partitions secured to the interior walls of said end portions, respectively, and forming a garment receiving compartment intermediate the ends of said device, each of said partitions having a substantially radial array of longitudinally extending closed conduits formed therein, each of said conduits being relatively elongated in the radial direction and being relatively narrow in a direction substantially perpendicular to said radial direction, and substantially conical deflector members secured to said partitions outside of said garment receiving compartment with their bases located at the centers of the arrays of conduits therein and with their apices directed away from said compartment.
5. A washing device for small garments and the like comprising in combination, a plurality of

mating portions which when mated form an elongated liquid tight chamber within said device, each of the portions forming an end of said device having a smoothly curved interior wall surface, and a hollow garment receiving container removably mounted in fixed position in said chamber intermediate the ends thereof, said container having opposite ends forming longitudinally spaced apart transverse partitions in said device having substantially radial arrays of longitudinally extending closed conduits formed therein, each of said conduits being relatively elongated in the radial direction and being relatively narrow in a direction substantially perpendicular to said radial direction, whereby upon 15 shaking said device liquid within the device is

adapted to pass from one end thereof to the other through said garment receiving container.

DONALD McCONAUGHEY.
